LOW TEMPERATURE R-F REACTOR PLASMA TUBE

Reid H. Curtis, Lombard, Ill., assignor to The Perkin Elmer Corporation, Norwalk, Conn., a corporation of New York

Filed June 28, 1968, Ser. No. 12,544

Term of patent 14 years

Int. Cl. D24—02

U.S. Cl. D16—2

FIG. 1 is a top plan view of a low temperature R-F reactor plasma tube showing my new design;

FIG. 2 is a front elevation view of the low temperature R-F reactor plasma tube of FIG. 1; and

FIG. 3 is a section view of a portion of the low temperature R-F reactor plasma tube of FIG. 1, taken along line 3—3.

I claim:

The ornamental design for a low temperature R-F reactor plasma tube, substantially as shown and described.
